UNITED STATES PATENT OFFICE

JAMES A. CAMERON, OF BROOKLYN, NEW YORK, ASSIGNOR TO CAMERON MACHINE COMPANY, OF BROOKLYN, NEW YORK, A CORPORATION OF NEW YORK

VARIABLE-BRAKE-RESISTANCE DEVICE FOR WINDING MACHINES

Application filed October 18, 1928. Serial No. 313,276.

This invention relates to winding machines for webs of flexible material, and has for its main object the production of means whereby coils of flexible material may 5 be so wound as to have such different characteristics of hardness as may be desired under different conditions or with different materials.

In an application filed July 28, 1926, Ser. No. 125,350, now Patent 1,707,047 issued March 26, 1929, is disclosed a winding machine in which the rise of a member, displaceable by the accumulation of wound material, is opposed at a diminishing rate by 15 means of counterweights or friction wedges. The present invention seeks to accomplish the same object by means of a variable brake resistance, and it may be used in place of the devices shown in my said earlier application or as an auxiliary in addition thereto.

In the accompanying drawings the invention is disclosed in several concrete and preferred forms in which:

Fig. 1 is a somewhat diagrammatic view 25 in side elevation of a winding machine embodying the invention.

Fig. 2 is a view partly in elevation and partly in section looking in the direction of arrow 2 of Fig. 3.

Fig. 3 is a view in side elevation looking in 30 the direction of arrow 3 of Fig. 2.

Fig. 4 is a view similar to Fig. 3, but showing a modified form of the invention.

The winding means may be of widely different types but is here exemplified by drums 35 1 and 2. The member displaceable by the accumulation of material may be either winding shaft 3 or top pressure roll 4, but the invention is here exemplified by applying it to the top pressure roll. As here shown, the top pressure roll and its carriage 5 are carried by flexible connections 6 and counter-weighting means 7, the connections passing here over sprocket wheels 8 and the counter-weighting means sliding on inclined ways 9.

Associated with, but not necessarily carried by, the displaceable member is a rotatable transmission element that rotates in response to the displacement of the member, 50 and a variable brake controlled by the dis-

placement of the member to oppose rotation of the element is provided. In Figs. 1, 2 and 3, the rotatable element is represented by a pinion 10, or its shaft, mounted on carriage 5. Preferably there are two pinions one at each side of the machine and these pinions engage stationary racks 11 so that, as member 4 becomes displaced and carriage 5 travels upwardly on guides 12, pinions 10 rotate in engagement with racks 11. 13 is a conventional representation of a brake applied to drum 14 pinned to the shaft carrying pinion 10. Spring 15 tends to relieve pressure of the brake band and arm 16 when actuated by a cam as 17 tends to increase the braking pressure. It will be understood that the greater the brake pressure, the greater the resistance to the upward displacement of member 4. It is apparent that by having differently shaped cams 17 or by adjusting 65 said cam (as by means of slot and bolt connection 18) various resistance effects to the rise of the displaceable member can be produced. As here shown, cam 17 is so shaped and adjusted that the greatest resistance to 70 rotation of element 10 occurs when the parts are in the position shown in Fig. 3, that is, at the beginning of the winding operation. As wound material accumulates on the winding shaft it rises, and so does the top pressure roller and its carriage, and eventually arm 16 reaches a point on cam 17 where it slopes and in consequence of this the braking pressure diminishes, the result being that less and less resistance is offered to rotation 75 of element 10 and displacement of member 4. 80

In Fig. 4 is shown a modification which is merely a reversal of the parts shown in Fig. 3. Here rotatable element 10^a is mounted on the framework and racks 11^a are mounted on carriage 5^a. So likewise cam 17^a is mounted to move with carriage 5^a. The operation of the parts would be the same as in Fig. 3.

I claim:

1. In a winding machine, a member displaceable by accumulation of wound material, and means to resist the displacement of said member including: a rotatable transmission element that rotates in response to the displacement of the member, a variable brake 95

to oppose rotation of the element, and means to automatically vary the pressure of the brake as movement of the displaceable member occurs.

5   2. In a winding machine, a member dis-
placeable by accumulation of wound mate-
rial, and means to resist the displacement
of said member including: a rack, a pinion
in rotatable engagement with the rack in
response to the displacement of the member,
a variable brake to oppose rotation of the
pinion, and means to automatically vary the
pressure of the brake as movement of the dis-
placeable member occurs.

15 3. In a winding machine, a member dis-
placeable by accumulation of wound mate-
rial, and means to resist the displacement
of said member including: a rotatable trans-
mission element that rotates in response to
20 the displacement of the member, a variable
brake to oppose rotation of the element, and
means to automatically diminish the pressure
of the brake as movement of the displaceable
member occurs.

25 4. In a winding machine, a member dis-
placeable by accumulation of wound mate-
rial, and means to resist the displacement
of said member including: a rack, a pin-
ion in rotatable engagement with the rack
30 in response to the displacement of the
member, a variable brake to oppose rotation
of the pinion, and means to automatically
diminish the pressure of the brake as move-
ment of the displaceable member occurs.

35 5. In a winding machine, a member displaceable by accumulation of wound material, and means to resist the displacement of said member including: a pinion carried by the displaceable member, a rack with which the pinion engages, a variable brake to oppose rotation of the pinion, and a cam to control, in response to the movement of the displaceable member, the application of the braking force of the brake.

45 6. In a winding machine, a member displaceable by accumulation of wound material, and means to resist the displacement of said member including: a pinion carried by the displaceable member, a rack with which the pinion engages, a variable brake to oppose rotation of the pinion, and a cam to lessen, in response to the movement of the displaceable member, the application of the braking force of the brake as the member becomes displaced.

50

55

55 7. In a winding machine, a member dis-
placeable by accumulation of wound mate-
rial, flexible connections and counterweight-
ing means carrying said member, and means
60 to resist the displacement of said member in-
cluding: a rotatable transmission element
that rotates in response to the displacement
of the member, a variable brake to oppose
rotation of the element, and means to auto-
matically vary the pressure of the brake as

movement of the displaceable member occurs.

8. In a winding machine, a member displaceable by accumulation of wound material, flexible connections and counterweighting means carrying said member, and means to resist the displacement of said member including: a rack, a pinion in rotatable engagement with the rack in response to the displacement of the member, a variable brake to oppose rotation of the pinion, and means to automatically vary the pressure of the brake as movement of the displaceable member occurs.

9. In a winding machine, a member displaceable by accumulation of wound material, flexible connections and counterweighting means carrying said member, and means to resist the displacement of said member including: a rotatable transmission element that rotates in response to the displacement of the member, a variable brake to oppose rotation of the element, and means to automatically diminish the pressure of the brake as movement of the displaceable member occurs. 80 85 90

10. In a winding machine, a member displaceable by accumulation of wound material, flexible connections and counterweighting means carrying said member, and means to resist the displacement of said member including: a rack, a pinion in rotatable engagement with the rack in response to the displacement of the member, a variable brake to oppose rotation of the pinion, and means to automatically diminish the pressure of the brake as movement of the displaceable member occurs. 95 100

Signed at the city of New York, in the
borough of Brooklyn, county of Kings, and 105
State of New York, this 11th day of October,
1928.

JAMES A. CAMERON.
